CLAIM

The ornamental design for a universal enclosure with cross-connect cabinet, as shown and described.

DESCRIPTION

FIG. 1 is a perspective view of a universal enclosure with cross-connect cabinet showing my new design;
 FIG. 2 is front elevational view thereof;
 FIG. 3 is a rear elevational view thereof;
 FIG. 4 is a side elevational view thereof, the opposite side being a mirror image of the side shown; and,
 FIG. 5 is a top plan view thereof.
 The bottom thereof forms no part of my design.

FIG. 3

FIG. 1

FIG. 2

FIG. 4

FIG. 5
